[57] CLAIM

The ornamental design for an irrigation spray nozzle, substantially as shown.

DESCRIPTION

FIG. 1 is a perspective view taken from the top, front and right side of an irrigation spray nozzle showing my new design, the rear being identical to the front shown; FIG. 2 is a right side elevational view thereof, the left side being a mirror image of the right side shown; FIG. 3 is a top plan view thereof; FIG. 4 is a bottom plan view thereof; and FIG. 5 is a cross section taken on the line 5—5 of FIG. 1.
